UNITED STATES PATENT OFFICE.

JOHN R. WOOD, OF NEWARK, NEW JERSEY, ASSIGNOR TO NEW PROCESS MULTI-CASTINGS COMPANY, OF NEWARK, NEW JERSEY, A CORPORATION OF NEW JERSEY.

MOLDING MACHINE.

Application filed July 28, 1922. Serial No. 577,666.

To all whom it may concern:

Be it known that I, JOHN R. WOOD, a citizen of the United States of America, residing at Newark, in the county of Essex and State of New Jersey, have invented certain new and useful Improvements in Molding Machines, of which the following is a full, clear, and exact description.

This invention pertains to the art of molding and is an improvement in the machines now used in foundry practice for forming the sand molds for casting any and all kinds of objects in metal. In this art, as heretofore practised, it has been usual to employ for the making of the sand molds what is known as a power or jolt machine, which is an apparatus containing a member similar or analogous in its action to a reciprocating piston or plunger which operated by steam or compressed air imparts a rapid succession of jolts to a support on which a flask containing a pattern is placed and into which sand of proper character and in proper condition is deposited, with the result that the jolting of the said support compacts the sand around the pattern and thus dispenses with the ramming by which such molds have commonly been made for many years.

In the use of such machines the usual practice is to place the drag member of a flask on the jolt table, and pack the sand therein. This is then removed and inverted and a cope member placed in its stead, packed in the same way, then removed, and associated with the inverted drag, after both the patterns or matched parts have been withdrawn. To produce a complete mold, therefore, requires either the simultaneous use of two jolt machines, or twice the length of time required for making one part or half of the mold. The primary object of this invention is to avoid this objection and to make a single machine capable of forming both the cope and drag members of the mold simultaneously under such conditions that they may be immediately associated to form a complete mold, without the use of any flask whatsoever.

To properly carry out this invention any machines of the type or kind known as power or jolt machines may be employed, but to form and use the sand molds produced, certain accessory parts and appliances are necessary if good molds are to be produced and the usual flasks for such molds dispensed with. These comprise means for retaining the sand in the cope when lifted from the table, means for withdrawing the patterns or match parts, and means for raising, inverting and shifting the drag half of the mold. A specific description of such parts follows.

The improved machine and its accessory parts are illustrated in the accompanying drawings, in which

Fig. 1 is a general view partly in elevation and partly in section, of the complete machine.

Fig. 2 is a similar view at right angles to that shown in the first figure.

Fig. 3 is a sectional view of the cope showing the means employed for withdrawing the pattern.

Fig. 4 is a sectional view of an associated cope and drag mounted on a carriage.

Fig. 5 is a view partly in elevation and partly in section of an associated cope and drag showing sand retaining means for the cope.

Fig. 6 is a view in side elevation of the same, and

Fig. 7 is a plan view of Fig. 5 looking from below.

The machine is mounted on a suitable base 1, and comprises, in the main, a cylinder 2 with a plunger 3, which by means of steam or compressed air introduced at 4 and reciprocating the piston, imparts a rapid jolting movement to a support 5, having a flat table 6. Machines of this general character are well known in the art, and that shown is intended merely as a typical illustration of a jolt machine.

On the table 6, a follow board 7 to which is clamped a drag 8 containing one part of the pattern or a matched part 9, is secured in any proper manner, and alongside

of this on and secured to the same table is a raised supporting table 10 having legs 11. This table 10 is formed in part of a central section 12, carried by a vertically movable support 13, comprising a cam 14 and handle 15 by means of which the said section may be raised to a level flush with the top of the table or lowered a given distance below it.

10 Upon this table 10 is placed a cope 16, the lower edge of which has holes to fit down over dowel pins 17 in the jolt table, so as to facilitate the adjustment of the cope. A matched plate or pattern 18 is laid on 15 and secured to the section 12.

The cope and drag, as indicated in Fig. 2 and other figures, may be capable of containing two or more patterns or matched plates, their size and capacity in this regard being arbitrary. When in position, sand of proper character and in proper condition is deposited in said cope and drag, from above, and by the operation of the jolt plunger is firmly compacted around 25 and over the patterns.

When these parts have been packed in this way and leveled off, a cover 19 is clamped on the drag and steam or compressed air is admitted to two cylinders 20, or other means employed, to raise the follow board and the drag by means of pistons and trunnions 22, extending from side plates carried by the said follow board. The trunnions carry segmental gears 23 and 30 rack bars 21 extend up from the table or cylinders 20, with which these gears mesh as the drag rises, and operate to turn the follow board and drag completely over, or 35 into the position shown in dotted lines in Fig. 1.

In place of the lifted drag, a car 24, Figs. 1 and 4, is then run in and the drag lowered and removed from the follow board placed thereon, and the pattern removed. 45 The clamps 25 securing the cover 19 to the drag are then removed and the car drawn off to one side. The section 12 of the table 10 is then lowered with the pattern thereon as shown in Fig. 3, and the cope 16 by 50 chains connected to trunnions 26 is then lifted from the table and carried to the drag with which it is associated in the relation shown in Fig. 4.

To permit the cope to be lifted off and transferred to the drag, it is necessary to employ a sand retaining means attached to the cope, and the means devised for this purpose is shown in detail in Figs. 4 to 7. The cope or section 16 of the flask is composed of the stationary or main part 16 and lower movable edges 27, which are connected to the main part by headed flanges 28 which slide in grooves in the same. At 55 each end of the part 16 are guides 29, in which slide bars or plates 30. To pins 31

set in the upper part of bars 30, are connected two knuckle joints composed of two pairs of links 32 pivoted together at their ends and pivoted to a stationary pin at 33. From the pivotal joints between the two 70 links extend pivoted connecting rods 34 engaging with pins 35 set at the corners of the side movable edges 27. Levers 36, pivoted to the side of the cope and to the bars 30 are used for raising and lowering 75 said bars.

When the cope has been placed on the drag the levers 36 are forced down with the result that the rods 34 spread apart the pins 35 and thus withdraw the sand retaining edges of the movable parts 27 from under the packed sand in the cope. The movable parts 27 have diagonal tongues 37 engaging slots in the end parts or slides 28 and when the first named parts are drawn 85 out they shift also the end parts.

While this operation is being performed the cope and drag members are locked together by clamps 38 but after the sand retaining slides are withdrawn these clamps 90 are released, and first the cope and then the drag flask members are lifted off from the sand leaving simply a mold of sand without a flask of any kind. When this mold is poured, it is enclosed in a relatively light 95 metal casing or box which is removable but which serves all the purposes of an ordinary flask. After the mold is poured this casing is taken off and applied to another mold. This is a well known device in the art. It 100 will be observed that the cope and drag elements are so formed that when associated they form a gradually tapering casing or flask around the sand mold so that they may be readily removed therefrom.

The above described improvements are defined in the following claims:

1. In a power or jolt molding machine the combination with a single support or table and means for jolting the same, of a vertically movable drag support mounted thereon and means for inverting the same and a drag carried thereby when raised, a stationary cope support also mounted on the table having a central movable section, and means for lowering said section to withdraw the pattern from the cope.

2. In a power or jolt molding machine the combination with a single jolt table of a vertically movable drag support mounted thereon and means for inverting the same with the drag when raised, an elevated cope support also mounted on the table having a central vertically movable section for supporting the pattern, means for lowering said section to remove the pattern and means for removing and assembling the cope and the inverted drag when packed.

3. In a power or jolt molding machine the combination with a single jolt table of a

vertically movable drag support mounted thereon carrying segmental gears, fixed rack bars adapted to engage with said gears when the said support is raised and to there-
5 by invert the same, and a stationary cope support alongside the drag support mounted on the table for the purpose set forth and

having a central vertically movable section for supporting the pattern and withdrawing the same when lowered.

In testimony whereof I hereto affix my signature.

JOHN R. WOOD.
